UNITED STATES PATENT OFFICE

2,457,488

LAMP SOCKET AND RESISTOR

Charles S. Penfold, Bronson, Mich., assignor to
H. A. Douglas Mfg. Co., Bronson, Mich., a corporation of Michigan

Application August 11, 1945, Serial No. 610,281

3 Claims. (Cl. 201—49)

1

This invention relates generally to lamp sockets and more particularly has to do with what is known in the trade as a miniature lamp socket preferably adapted for detachable connection with respect to an instrument panel of an automotive vehicle or other suitable mounting.

More specifically, an important object of the invention is to provide such a device with improved resistance means for reducing the intensity of the current to the lamp carried by the socket.

Another object is to provide means whereby the resistance means and socket are permanently secured together in a manner whereby to insure positive electrical connections between the parts.

Other objects and advantages of the invention will appear after reading the description hereinafter set forth in conjunction with the drawings annexed hereto, wherein two embodiments of the invention are illustrated.

In the drawings:

Figure 1 is a side view of lamp socket, partly in section, showing the invention applied thereto;

Figure 2 is a rear end view of the socket and resistance means;

Figure 3 is a section taken through a part of the device illustrating more in detail certain of the principles of design and construction embodied in the assembly; and

Figure 4 is another embodiment of the invention.

Referring to the first embodiment of the invention illustrated in Figures 1 through 3, of the drawing, numeral 1 represents a tubular lamp socket body provided with holding means 2 adjacent its front extremity for detachable disposition in a circular opening 3 of a mounting 4 to support the body. The rear extremity of the body carries resistance means 5. A miniature lamp 6 is seated in the socket body and a terminal 7, mounted on a carrier 8 of insulating material, is pressed into engagement with the contact 9 of the lamp by a helical spring 10. The holding means 2 includes an annular base 11 provided with a plurality of forwardly extending fingers which are designed to snap into the opening and engage its margins.

A ring 12 is utilized to attach the holding means to the socket, and includes an axially extending portion 13 and a pair of spaced apart inwardly extending radial portions 14 and 15. The front extremity of the socket body is provided with an outwardly extending radial flange 16, of a diameter substantially corresponding to the diameter of the base 11 of the holding means,

located in the ring 12. The body is insulated electrically from the mounting. This is preferably accomplished in part by disposing a pair of corresponding apertured washers 17 and 18 between the base 11 and flange 16, and flange 16 and radial portion 15, respectively, and placing a tubular insulator 50 between the peripheries of the base 11, washers 17 and 18, and the axial or base portion 13 of the ring. It will be noted that the base portion 11 engages the radial portion 14 of the ring; that the latter engages this mounting; and that the ring cannot engage the socket body due to the provision of a clearance aperture 100. The ring or collar thus serves to firmly secure the holding means and associated parts adjacent the front extremity of the socket together.

The resistance means 5 and means for attaching same to the socket will now be described. 20 The resistance means 5 is preferably made in the form of a moulded annular block of carbon permanently secured adjacent the rear end wall 19 of the socket by a tubular conductor 20. The conductor extends through the wall 19, through an opening in the resistance means, and is flanged at 21 to engage the inner surface of the wall 19 and at 22 to engage a considerable area of the rear side of the resistance means. An insulated conductor 23 extends through the tubular conductor 20 and is provided with the terminal 7, above referred to. A tubular sleeve 24 of insulating material is received in the opening provided in the resistance means and surrounds the tubular conductor 20. A flat terminal member 25 is carried by the insulating sleeve 24 and an insulating washer 26 is carried by the tubular conductor 20. The terminal member 25 is preferably provided with a take-off 27 adapted to detachably accommodate a plug conductor terminal.

When the resistance means 5 is subjected to an electric current, or is otherwise subjected to heat it expands and on cooling contracts. In order to compensate for any variation in this respect 45 and at all times maintain the resistance means in intimate electrical engagement or bearing relation with the terminal member 25 and flange 22 and the flange 21 in engagement with the end wall 19 of the socket, resilient means 28, carried by the sleeve 24, is preferably interposed between the washer 26 and the terminal member 25. The resilient means may take any form, provided same produces an axial force when compressed or placed under tension. The resistance means, 55 preferably in the form of an apertured spring

disc, also portions to press the insulating washer 26 and radial flange 21 of the tubular conductor 20 against the end wall 19 of the socket body. By this arrangement the socket body is insulated from the mounting 4, and the current is caused to travel in a predetermined path. Also the parts are substantially held against vibration.

When the parts are assembled as illustrated in Figures 1 through 3, and connected in an electric circuit, current will pass from the terminal 7 attached to the insulated conductor 23 to the center contact 9 on the lamp, and from the lamp base to the terminal take-off member 25 through the intermediation of the socket body, tubular conductor 20, and resistance means 5. The resistance means thus serves to reduce the intensity of the current supplied to the bulb, and is particularly desirable for use in a system where certain illuminating devices require more current than others.

In the modified assembly illustrated in Figure 4, resilient means 29, corresponding in character to the means 28, functions to urge the resistance means 30 directly against the end wall 31 of a socket body 32. The resistance means 29 is mounted on an insulating sleeve 33 within which is disposed a tubular member 34. The tubular member 34 is provided with radial flanges 35 and 36 adjacent its inner and outer extremities. An insulating washer 37 and a terminal take-off member 38 are also preferably carried by the insulating sleeve 33, the washer being interposed between the inner flange 35 and end wall 31 and the member 38 between the resistance means 30 and the resilient means 29. In the modified arrangement, the current will pass from a contact 39 attached to the conductor 40 to the center contact on the lamp, and from the lamp base to the terminal take-off member 38 through the intermediation of the socket body 32 and the resistance means 30. It will be manifest that the resilient means 29 functions to hold the desired parts in intimate contact and prevent vibration as in the case of the first embodiment of the invention, and this current does not pass through the tubular member 34.

Having thus described my invention, it is obvious that various other modifications may be made in the same without departing from the spirit of the invention; and, therefore, I do not wish to be understood as limiting myself to the exact forms of construction, arrangements, and combination of parts herein shown and described.

I claim:

1. A lamp socket and resistance element assembly comprising a sheet metal tubular casing having on one end a lamp receiving opening end means for detachably mounting the assembly on

a support, a metal sleeve extending axially from the opposite end of said casing having a passage communicating with the interior of the casing for accommodating a conductor wire and having an outwardly extending flange on the end thereof remote from said casing, a layer of insulating material surrounding said sleeve, a resistance element mounted on said layer of insulating material and electrically connected to said sleeve by engaging said flange, a terminal unit also mounted on said layer comprising a metal mounting part disposed between said casing and said resistance element and having electrical contact with the latter, and an insulating washer disposed between said part and said casing whereby current will be caused to flow from said casing through said sleeve, resistance element, and said terminal unit.

2. A socket and resistance element assembly comprising a sheet metal housing having a plug receiving opening at one end and an inturned flange at its opposite end, a sleeve extending axially from said flanged end of said housing having an outwardly extending flange within the latter and abutting the inturned side of said first mentioned flange in interlocking engagement therewith, a solid type resistance element mounted on and surrounding said sleeve having an extremity in abutting engagement with said inturned flange, an outwardly extending flange on the end of said sleeve remote from said housing and adjacent the opposite extremity of said resistance element, and resilient means interposed between said last mentioned flange and said opposite extremity of said resistance element for pressing the element against said inturned flange.

3. The structure defined in claim 2, including terminal means disposed between said element and said resilient means whereby said terminal means is also pressed against said element.

CHARLES S. PENFOLD.
